ADJUSTABLE BREAST BEAM COVER FOR LOOMS

Ed Dorsey West, Laurens, S.C.

Application December 31, 1957, Serial No. 706,501

6 Claims. (Cl. 139—1)

This invention comprises a novel and useful adjustable breast beam cover for looms and more particularly relates to an attachment adapted to be mounted adjacent the breast beam of a loom to constitute a cover or shield for the same and also comprise a shelf or receptacle.

The primary object of this invention is to provide an attachment specifically adapted to be readily applied to conventional types of looms to afford a shield or guard for the breast plate thereof and to further provide a shelf or receptacle for receiving tools or other objects.

A further object of the invention is to provide an attachment for looms which may be easily applied to or removed from a loom where it is desired to afford protection for the breast beam and the cloth passing thereover or to obtain access to the breast beam.

Yet another object of the invention is to provide a breast beam attachment for looms of such construction that the same may be readily disposed in stacked relation upon each other in a convenient manner.

And a final important object of the invention to be specifically enumerated herein resides in the provision of a breast beam cover for looms which may be mounted upon conventional loom structure and may be vertically adjusted with regard to the breast beam in order to adapt the device to different conditions of operation and to different types of looms.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of the breast beam cover comprising an attachment for looms and constituting the subject matter of the present invention;

Figure 2 is a detailed view in vertical transverse section through a portion of a loom structure showing the breast beam and the fell of the cloth passing thereover, a take-up roller stand and the breast beam cover of this invention operatively associated with these elements, there being shown in dotted lines therein the manner in which a breast beam cover of this invention may be stacked in nested relation upon another cover in accordance with this invention;

Figure 3 is a vertical longitudinal sectional view taken substantially upon the plane indicated by section line 3—3 of Figure 2 and showing the manner in which the breast beam cover of this invention is adjustably carried by the take-up roller stands of the loom; and

Figure 4 is a detail view in horizontal section taken substantially upon the plane indicated by the section line 4—4 of Figure 3 and showing the manner in which an end of the breast beam cover is mounted for vertical sliding movement in a portion of the take-up roller stand of a loom.

The breast beam cover attachment for a loom forming the subject matter of this invention may be applied to numerous conventional types of looms. It is particularly

2

adapted for use with the well-known Draper loom, and in the drawings the numeral 10 designates the breast beam of this loom over which the fell 12 of the fabric being woven is passed during the weaving operation.

5 Shown at 14 are portions of the stands for the take-up rollers, not shown, the upper ends of these stands have vertically extending channels 16 therein which have a bottom wall as at 18, see Figures 2 and 3.

Use is made of this channel and bottom wall structure of the take-up roller stands as a means for adjustably supporting the breast beam cover designated generally by the numeral 20 and which forms the subject matter of this invention. It will be understood however that the breast beam cover may be adapted to other types

15 of looms by making use of some other of the supporting structure or framework of the loom, it being only essential that the breast beam cover shall be mounted in closely spaced relation to the breast beam for covering or shielding the front thereof and for overlying the top surface thereof as set forth hereinafter.

The breast beam cover attachment of this invention consists of a vertical plate 22 of any suitable material which extends across the face of the loom in closely spaced relation to the vertical face of the breast beam.

25 10. The opposite ends of the vertical plate 22 are slidably received in the channel 16 of the take-up roller stands 14 in the manner clearly shown in Figures 3 and 4. Disposed in internally threaded bores 24 opening from the bottom surface of the vertical plate 22 are down-

30 wardly projecting adjusting screws 26 whose heads 28 are adapted to rest upon the bottom wall 18 and support the vertical plate 22 thereon as will be readily seen from Figure 3. Obviously, by adjusting the screws 26, the plate 22 may be raised or lowered relative to the 35 breast beam for a purpose to be subsequently set forth.

Intermediate its ends the top wall 30 of the breast beam is vertically recessed as at 32 to receive a horizontal laterally extending plate 34. Suitable fasteners, such as the screws 36, are employed for securing this plate to

40 the vertical plate in lateral relation thereto. The plate 34 is of such size that the same at its outer end will overlie the top or horizontal surface of the breast beam 10 and of the fell 12 entrained thereover as will be apparent from Figure 2. The adjusting screws 26 provide a means 45 for adjusting the vertical clearance of the horizontal plate 34 with the breast beam.

Disposed along the marginal edges on the top sides of the horizontal plate 34 are upstanding beads or rims 38 which cooperate with the plate to define a tray. By 50 means of this construction small objects such as tools or the like may be safely placed upon the tray when working upon a loom thus preventing the soiling or damaging of the fell 12 passing over the breast beam.

Secured to the underside of the horizontal plate 34 55 and to the inward face of the vertical plate 22 is a reinforcing strip 40 of any suitable material. As shown in Figure 2 this strip has a longitudinally extending groove 42 which is of the same cross-sectional shape as that of one of the ribs or beads 38 of the horizontal plate 34

60 in order that a series of the attachments may be stacked upon each other with the grooved reinforcing strip 40 of one attachment being seated upon the bead 38 of the plate therebeneath as shown in dotted and full lines in Figure 2. Thus, when it is desired to remove an attachment in order to obtain access to the breast beam or other parts of a loom, the breast beam cover of that loom may be removed and stacked as shown in Figure 65 2 upon the breast beam cover of an adjacent loom. This prevents cluttering of the working space between the looms by placing the cover, tools or the like upon the floor as has been possible heretofore.

70 As will be readily understood, the member 42 serves

both to reinforce the connection of the horizontal and vertical plates 34 and 22, respectively, and also provides a means to assist in seating one attachment upon another in a nested or stacked relation.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. An adjustable breast beam cover for looms of the type including a loom frame having a breast beam mounted thereon and take-up roller stands with vertical channels therein, said cover comprising a vertical plate extending across the face of a loom in spaced relation to the vertical face of a breast beam and with its opposite ends received and supported in said channels, a horizontal plate mounted upon said vertical plate and extending laterally therefrom to overlie the top surface of a breast beam in closely spaced relation thereto and provide a shelf, adjustable support means mounting said vertical plate upon said loom frame for vertical adjustment relative to said breast beam whereby to vary the vertical space therebetween.

2. The combination of claim 1 including upstanding marginal ribs on the top surface of said horizontal plate to provide a tray.

3. An adjustable breast beam cover for looms of the type including a loom frame having a breast beam mounted thereon comprising a vertical plate extending across the face of a loom in spaced relation to the vertical face of a breast beam, a horizontal plate mounted upon said vertical plate and extending laterally therefrom to overlie the top surface of a breast beam in closely spaced relation thereto and provide a shelf, adjustable support means mounting said vertical plate upon said loom frame for vertical adjustment relative to said breast beam whereby to vary the vertical space therebetween, an upstanding rib on the top surface of said horizontal plate along the marginal edge thereof overlying said vertical plate, a longitudinally grooved strip secured to the adjacent inner and lower surfaces respectively of said vertical and horizontal plates adjacent their junction, said strip being positioned for receiving therein the upstanding rib of another cover when a pair of covers are disposed in nested overlapping relation.

4. An adjustable breast beam cover for looms of the type including a loom frame having a breast beam mounted thereon comprising a vertical plate extending across the face of a loom in spaced relation to the vertical face of a breast beam, a horizontal plate mounted upon said vertical plate and extending laterally therefrom to overlie the top surface of a breast beam in closely spaced relation thereto and provide a shelf, adjustable support means mounting said vertical plate upon said loom frame for vertical adjustment relative to said breast beam whereby to vary the vertical space therebetween, said adjustable support means including adjusting screws threadedly connected to said vertical plate and depending therefrom and engaging said frame.

5. In a loom having a frame with a breast beam mounted thereon and take-up roller stands on said frame with vertical slots in said stands; an adjustable breast beam cover comprising a vertical plate having its ends slidably received in said take-up roller stands' slots, said vertical plate being disposed in spaced relation to the front face of said breast beam, a horizontal plate mounted upon said vertical plate and extending horizontally therefrom and overlying the top surface of said breast beam in vertically spaced relation to provide a shelf, adjusting means on said vertical plate and cooperating with said frame for vertically adjusting said vertical plate in said slots whereby to adjust the clearance between said horizontal plate and said breast beam.

6. The combination of claim 5 including an upstanding rib on the top surface of said horizontal plate along the marginal edge thereof overlying said vertical plate, a longitudinally grooved strip secured to the adjacent inner and lower surfaces respectively of said vertical and horizontal plates adjacent their junction, said strip being positioned for receiving therein the upstanding rib of another cover when a pair of covers are disposed in nested overlapping relation.
